UNITED STATES PATENT OFFICE.

ROGER W. DISERO, OF CLEVELAND HEIGHTS, OHIO, ASSIGNOR TO THE W. S. TYLER COMPANY, OF CLEVELAND, OHIO, A CORPORATION OF OHIO.

DOOR HANGER.

Application filed November 7, 1925. Serial No. 67,507.

The present invention, relating, as indicated, to door hangers, is particularly directed to an improved hanger for use in sliding doors which are subject to sudden acceleration and deceleration when started from rest and when brought to a stop after opening, such, for example, as elevator doors used in buildings. It is important that such doors be opened as rapidly as possible and also be brought to rest after the opening, and it is in such operation of a heavy metal door which is hung from an overhead trackway, as is the case in such constructions, that a very considerable force is exerted, due to the momentum of the door around the furthest points of support on the overhead trackway. The result of this operation is that one end of the door tends to rotate with respect to the other, exerting in some cases a tremendous force against the trackway and actually spreading or spacing apart the upper and lower trackways. After repeated operation of this character the trackways become sprung and eventually break, and when such breakage occurs it is frequently found that the anti-friction elements interposed between the hangers and the trackways drop out because of the widening of the upper and lower trackways, on which the door is supported.

It is the purpose of the present invention to provide a door hanger or supporting means which shall not be subject to the above objections and which shall be capable of continued use without spreading or breakage even after repeated severe operation. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—

Fig. 1 is a perspective view of my improved hanger showing a portion of an elevator door secured therefrom; and Fig. 2 is a transverse vertical section showing a modification of the hanger illustrated in Fig. 1.

Referring now to Fig. 1, there is shown an elevator door 1 provided with a support

ing element 2 which is secured to a movable element 3 in the form of a longitudinally extending bar having raceways 4 and 5 in its upper and lower surfaces. Received partly in these raceways and partly in corresponding grooves 6 and 7 in track elements 8 and 9 are disposed antifriction elements in the form of balls 10 which roll along the raceways as the movable element 3 and the elevator door 1 are moving to open or close the door.

The supporting means for the track elements 8 consists of a channel member 9 provided with two parallel arms 10 and 11. This element is formed to have the arms 10 and 11 substantially rigid, that is, to maintain these arms against any spreading or lateral deflection under any force that can be exerted by opening or closing the door which is supported therebetween. Each of the arms 10 and 11 of the channel member 9 is of substantial thickness and is provided with a rectangular recess 12 in its inner face, that is, in the face opposite to the other arm, in which is snugly fitted the track elements 8, these elements then being secured therein by screws or rivets 13, as may be desired, although it will be understood that the force exerted upward on the upper track 8 and downwardly on the lower track 8 is transmitted through the track directly to the arms 10 and 11 and is not resisted by the securing elements 13. The track elements 8 are formed to fit snugly into the recess 12 in the arms 10 and 11 in order that these elements may be backed up and supported throughout their entire length and on at least two, and to some extent three, sides so that any deflection in the track elements is completely prevented since at all points along their length these elements are rigidly supported by the unyielding and heavy arms 10 and 11.

With the present construction it is possible to employ wear resisting materials, such as hardened steel or alloy steel in the track elements and to then support these against any deflection by the less expensive rigid brackets 9, which in turn are supported by either the side wall of the elevator car, if the device is employed for an elevator, or by the wall of the elevator shaft if the device is employed with the shaft doors rather than the doors of the car itself.

I have found by thorough tests of the construction above described that under any

ordinary usage and throughout any reasonable period the channel members will sufficiently support the trackways so that there will be no widening of the space between the trackways and no opportunity for the anti-friction elements to drop out from between the element 8 and the two trackway elements 8, while the wear on the hardened or wear-resisting trackways is substantially negligible.

My improved hanger may be used in various forms, and one modification of the device just described is shown in Fig. 2, in which an I-beam or I-shaped member 15 is employed, provided with two pairs of spaced arms 16 and 17, and 18 and 19, between each of which are mounted movable elements 20 and 21 carried on anti-friction elements 22. Each of the elements 20 and 21 corresponds to movable element 3 of the device of Fig. 1, and constitutes the member from which the door is supported. In this construction, as in the one previously described, wear-resisting track members 25 are set into suitably formed recesses in the opposite faces of the arms 16 and 17, and 18 and 19, of the channel member.

It will also be understood that individual elements of the character illustrated in Fig. 1 may be assembled together in various combinations when more than one door is to be supported, either back to back, which would give a construction corresponding somewhat to Fig. 2, or front to back, in which the open portion of one channel would be disposed directly against the back of another.

Other modes of applying the principle of my invention may be employed instead of the one explained, change being made as regards the mechanism herein disclosed, provided the

means stated by any of the following claims or the equivalent of such stated means be employed.

I therefore particularly point out and distinctly claim as my invention:

45

1. A door hanger comprising a heavy rigid channel member provided with recesses formed in opposite faces of the arms of said channel, trackways mounted in such recesses and rigidly supported therein, a moving element disposed between said trackways, and anti-friction elements interposed between said element and said trackways.

2. A door hanger comprising a heavy rigid channel member having two spaced horizontal arms each provided with a recess in the face opposite to the other of said arms, and wear resisting tracks set in such recesses and rigidly supported therein.

3. A door hanger comprising a heavy rigid channel member having two spaced horizontal arms each provided with a rectangular recess therein in the face opposite to the other of said arms, and rectangular wear resisting tracks set into such recesses, said tracks being rigidly supported on three sides by the walls of such recesses.

4. A door hanger comprising a channel member substantially rigid against deflection between the arms thereof, and trackways rigidly secured to the opposite faces of the arms of said channel.

5. A door hanger comprising a rigid member having substantially rigid heads each provided with recesses on its inner face, wear resisting trackways set into such recesses, and means securing the same therein.

Signed by me, this 20th day of October, 1925.

ROGER W. DISBRO.
